(57) CLAIM

The ornamental design for a lounge, as shown and described.

DESCRIPTION

FIG. 1 is a front left perspective view of a lounge according to a first embodiment;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a front, left perspective view of a lounge according to a second embodiment;

FIG. 8 is a front view thereof;

FIG. 9 is a rear view thereof;

FIG. 10 is a left side view thereof;

FIG. 11 is a right side view thereof; and,

FIG. 12 is a top view thereof.

The double dashed lines, in FIGS. 7-12, located down the center of the lounge, is a boundary line, representing the bounds of the claim and form no part of the claimed design. The broken lines shown in the drawings depict portions of the lounge that form no part of the claimed design.

1 Claim, 12 Drawing Sheets
